BOMB RELEASE MECHANISM

Earl W. Chafee, Great Neck, and Howard C. Van Auken, Manhasset, N. Y., assignors to The Sperry Corporation, a corporation of Delaware

Original application February 26, 1937, Serial No. 128,034. Divided and this application February 8, 1945, Serial No. 576,762

9 Claims. (Cl. 89—1.5)

1

This invention relates to an automatic bomb release mechanism and is a division of the application of Earl W. Chafee and Howard C. Van Auken, Serial No. 128,034, filed February 26, 1937, and now Patent No. 2,371,606, issued March 20, 1945, relating to bomb sights.

An object of the invention is the provision of a simple releasing arrangement by which bombs may be accurately dropped upon a target.

Other objects of the invention will appear in the following description given with the aid of the accompanying drawings, of which

Fig. 1 shows schematically a portion of the computing mechanism of a bomb sight;

Fig. 2 shows an arrangement for releasing bombs according to a preferred embodiment of the invention; and

Figs. 3 and 4 show details of a warning signal annunciator.

A portion of the bomb sight of the parent case, believed sufficient for an understanding of the present invention, will now be briefly described.

Reflecting prism 20 is adjustable about an axis 21 for the purpose of tracking a target. Adjustment is accomplished by bell crank 22 pivoted at 23 and provided at its lower end with a channel member 24 in which is positioned an arm 25 attached to the prism. The bell crank is turned on its pivot by a member 26 which engages the upper end thereof, the member being controlled by rod 27 reciprocated by sight angle cam 28. Spring 29 attached to the bell crank keeps the bell crank, member 26, rod 27 and cam 28 in engagement.

In the computing mechanism shown, four three-dimension cams are used, of which cams 35 and 36 are supported by a shaft 37. Both cams are secured to a sleeve 38 which is free to turn on shaft 36 but is restrained from longitudinal movement thereon by fixed collars 39 and 40. Shaft 37 and the cams thereon are translated according to vertical velocity of glide by a rack 41 formed in the shaft which meshes with a gear 42 on shaft 43 on which is secured another gear 44 meshing with gear 45 positioned by means of knob 46, shaft 47, and gear 48. Knob 46 is used to set the vertical velocity of glide into the sight and controls mechanism, not shown, which effects necessary adjustment of the sight when the airplane is not flying a level course.

The knob is kept at a fixed position when the course is level by an arrangement including gear 49 on shaft 50 which meshes with gear 45. The shaft 50 is so positioned by the knob that when

2

the course is level, a finger 51 drops into a notch formed in the edge of a disc 52 secured to shaft 50.

When the course is not level, shaft 55 turns, but is otherwise stationary. The shaft, when in motion, is turned in proportion to the rate of change of altitude, and drives, through gears 56 and 57, a shaft 58 carrying long pinion 59 in mesh with gear 60 secured to cam 36, the long pinion serving to rotate cam 35 as well as cam 36. However, when the course is level, it will be understood that these cams are stationary.

Lift pin 61 of cam 35 translates cam 62, which is displaced in rotation by gear 63 secured thereto, the gear being in mesh with long pinion 64, driven by gears 65 from shaft 66 which turns in proportion to ground speed. Shaft 66 is driven, in the mechanism shown from the ground speed dial 67, by means of gear 68, shaft 69 and gears 70.

Cam 62 is also further displaced in translation with respect to lift pin 61 according to the ballistic coefficient of different bombs to take care of the difference in time of fall thereof. This displacement is made by a knob 75 arranged to be set with respect to a scale 76. The knob is mounted on an extension of lift pin 61 which is threaded at 77 into an enlarged extension 78 from cam 62. Turning of knob 75 positions the cam axially on the lift pin extension.

Cam 62 combines ground speed with a factor proportional to the time of fall of the bomb and also an altitude ratio so that its lift pin 79 is displaced according to whole range.

Lift pin 79 displaces a long lever 80 which is also displaced by lift pin 81 of cam 82. The lever is used to operate one element of the novel bomb release mechanism of the present invention in accordance with the combined displacement of both lift pins which represents whole range less trail.

Cam 82 is translated by lift pin 83 of cam 36. The inputs for the latter cam have been described. Cam 36 is laid out to translate cam 82 in proportion to the square of the time of fall (T₀)² and the altitude ratio.

Cam 82 is positioned in rotation from shaft 85 according to a trail value. Cam 82 is so laid out as to displace its lift pin 81 in accordance with the computed value of trail and this value is so modified by lift pin 79 that the left hand end of lever 80 is displaced in accordance with whole range corrected for trail.

Lever 80 is pivoted to a bar 89 slidably supported in a bracket 90, Fig. 2. A support 92 preferably of insulating material having an arm 93

attached thereto by pivot 94 is secured by screws 91 to bar 89. Spring 95 holds the arm against adjustable stop screw 96. A contact spring 97 is secured to one edge of the insulating support 92, while another contact 98 is attached to pivoted arm 93 by a screw and nut 99. These contacts are moved with their supports in accordance with the relative displacements of lift pins 79 and 81, and cooperate respectively with another set of contacts 100 and 101, which are moved according to sighting angle. The operating mechanism for these contacts will now be described.

Shaft 105 is coupled to worm wheel 106 by slip clutch 107. Worm 108 is driven by means not shown effective to turn wheel 106 and shaft 105 at a rate in proportion to ground speed, to a position proportional to the tangent of the instantaneous sighting angle.

Gear 109 on shaft 105 meshes with a rack 110 formed on the edge of a slide 111 supported for parallel movement with respect to member 89 by guides 112 and 113.

A non-conducting bracket 115 secured to slide 111 carries a contact block 116 to which is secured the contact 100, which is so disposed thereon as to engage contact 97 at a predetermined relative position of member 89 and slide 111. The bracket also supports contact 101 so disposed as to make with contact 98 on arm 93 at a predetermined relative position of member 89 and slide 111 beyond the position at which contacts 97 and 100 are first closed. Contact 100 is elongated and once in engagement with contact 97 will maintain sliding contact therewith while contacts 98 and 101 are moved towards each other until both sets of contacts are closed.

A contact strip 117 is engaged by a contact spring 118 supported by a bracket 119 fastened to guide 113. The contact spring is suitably insulated from the guide and is used to maintain a connection for the contacts held by bracket 115 with external circuits, the connection in the present embodiment being with one pole of a source of potential 125.

The contact arrangement just described may be used to operate a warning circuit and subsequently a bomb release circuit. In Fig. 2, contacts 97 and 100, when closed, operate an annunciator device for giving a warning signal. In a preferred arrangement, a winding 126 of an annunciator has one terminal connected to a pole of the source of potential 125, and the other terminal connected through the tongue 127 and back contact 128 of a bomb release relay to contact 97. This circuit is completed to the opposite pole of the source of potential when contacts 97 and 100 engage, the circuit being through contact strip 117 and wiper 118.

Winding 126 may operate a suitable armature arrangement for deflecting a warning flag 130 into the optical path of a sighting instrument where it will be observed by the bombardier. The details of a suitable arrangement of this kind are shown in Figs. 3 and 4.

Shortly after the warning signal, bomb release contacts 98 and 101 close. These contacts control a bomb release circuit which is susceptible of numerous modifications, a preferred arrangement being shown in Fig. 2 where the winding 129 of a relay has one terminal connected to one pole of the source of potential 125, the other terminal of the winding being connected to the opposite pole on closure of contacts 98 and 101, the circuit including contact strip 117 and wiper 118.

When the winding 129 of the relay is energized, tongue 127 breaks with back contact 128, thus disconnecting the warning signal annunciator winding 126. Tongue 127 then engages its front contact 132, thus effectively short-circuiting contacts 98 and 101.

If desired, an additional electromagnetic device such as is indicated by reference character 133 may be operated directly by the circuits described for bomb release purposes. The device 133 is shown as being connected in parallel with winding 129 of the relay.

As the success of the bomb dropping operation depends largely upon the time at which the bomb is dropped, it is evident that it is very important to prevent the bomb dropping contacts from burning as that would be equivalent to a gradual change of their relative position. In the circuits disclosed herein, the contacts are protected by the arrangement which allows the contacts to close a circuit but prevents them from ever breaking a circuit, thereby eliminating destructive arcing at the contact points.

As the aircraft is approaching the target, contacts 97 and 100 will eventually engage and close a circuit operating annunciator 126—130. Next, contacts 98 and 101 engage, operating the relay 129 and also the solenoid device 133 in accordance with one embodiment of the invention. The back contacts 127 and 128 of the relay break, de-energizing the warning signal. When front contacts 127 and 132 make, they short-circuit bomb release contacts 98 and 101, and also establish a holding circuit for the relay through contacts 97 and 100 and the relay will remain operated as long as these contacts are closed. Contacts 97 and 100 are so arranged as to remain closed long after contacts 98 and 101 have opened. With the further relative movement of member 89 and slide 111, which may continue for some time, arm 93 will be turned in a counter-clockwise direction, initially by the engagement of contacts 98 and 101 and later by the engagement of a roller 134 pivoted to arm 93 with insulating bracket 115, which separates contacts 98 and 101 so that no appreciable sliding movement may occur therebetween to wear the contacts. At the time when the contacts 98 and 101 separate, they are short-circuited by relay contacts 127 and 132, and thus no arcing occurs.

During return of member 89 and slide 111 to their initial position, contacts 98 and 101 close again and later re-open, but while they are closed they remain bridged by contacts 127 and 132. With the arrangement described, it is possible to maintain the mechanical dimensions of the main contacts so that no appreciable change occurs therein after many operations, which would not be the case if the contacts were permitted to break the rather heavy current required for the operation of the circuits.

Since many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

- In a bomb release mechanism for a bomb sight having a computing mechanism, a pair of members each movable independently under control of the computing mechanism in accordance with different computations, contact means so

disposed on the respective members as to be brought into engagement at predetermined relative positions of the members, and electrical warning signal and bomb release circuits successively operated in the order named by the contact means.

2. In a bomb release mechanism for a bomb sight having a computing mechanism, a pair of members disposed for parallel movement, means for moving the members independently under control of the computing mechanism in accordance with different computations thereof, contact means comprising a plurality of sets of independent contacts disposed so as to be successively actuated by the members at predetermined positions thereof, an electrical warning circuit controlled by a first operated set of said contacts and an electrical bomb release circuit controlled by a subsequently operated set of said contacts.

3. In a bomb release mechanism for a bomb sight having a computing mechanism, a pair of members disposed for relative parallel movement under control of the computing mechanism, contact means comprising a plurality of sets of independent contacts disposed so as to be successively actuated by the members at predetermined positions thereof, an electrical warning circuit controlled by a first operated set of said contacts, a bomb release circuit including a relay controlled by a subsequently operated set of said contacts, and means for connecting a protective shunt about the last-mentioned contacts controlled by the relay.

4. In a bomb release mechanism for a bomb sight having a computing mechanism, warning contact means, bomb release contact means, means controlled by the computing mechanism for operating the contact means successively in the order named, an annunciator device, an operating circuit therefor controlled by the warning contact means, and a relay controlled by the bomb release contact means having contacts interconnected in said operating circuit adapted to disable the annunciator device.

5. In a bomb release mechanism for a bomb sight having a computing mechanism, warning contact means and bomb release contact means controlled by the computing mechanism successively in the order named, a relay controlled by the bomb release contact means, and contact means controlled by the relay when operated for connecting a protective shunt across the bomb release contact means.

6. In a bomb release mechanism for a computing bomb sight having a computing mechanism, warning contact means and bomb release contact means controlled by the computing mechanism of the bomb sight successively in the order named, an annunciator circuit controlled by the

warning contact means, a relay controlled by the bomb release contact means, relay contacts and circuit means connected thereto effective when operated to disable the annunciator circuit and to connect a protective shunt across the bomb release contact means, and other circuit means including said warning contact means for holding the relay when once operated in operated condition independently of the bomb release contact means.

7. In a bomb release mechanism for a bomb sight having a computing mechanism, warning contact means, a warning circuit controlled thereby, bomb release contact means, bomb release circuit means controlled thereby, means controlled by the computing mechanism according to the computations thereof for first closing the warning contacts and then closing after a predetermined interval the bomb release contact

10 20 means, and means controlled by the bomb release circuit on the closing of the bomb release contact means for disabling the warning circuit and thereafter shunting the bomb release contact means to protect the latter.

25 30 35 40 45 50 55 8. A bomb release mechanism for a bomb sight, including a warning relay, a transfer relay, a bomb release relay, a relatively movable pair of normally open warning contacts adapted on movement from a neutral position to engage and to energize thereby said warning relay at a given time interval before dropping the bomb, a relatively movable pair of release contacts, circuits controlled thereby adapted to energize said bomb release relay and said transfer relay in parallel, multiple switch means operated by said transfer relay, circuits controlled thereby adapted on the operation thereof to simultaneously deenergize said warning relay and to short-circuit said release contacts, and to electrically lock said release relay and said transfer relay, said warning contacts, upon being separated during the return to their neutral position, breaking said electrical lock.

9. In a bomb release mechanism for a bomb sight, a bomb release circuit, a first pair of relatively movable contacts controlled by the bomb sight, means brought into action by said contacts on engagement thereof to give a timed warning signal, a second pair of movable contacts controlled by the bomb sight adapted on engagement to make but not to break a bomb release circuit, means in said circuit and operated by said contacts to cause release of the bomb, and a second means in said circuit to cause interruption of said warning signal and to simultaneously transfer control of said circuit from said second pair of contacts.

EARL W. CHAFFEE.
HOWARD C. VAN AUKEN.
